UNITED STATES PATENT OFFICE.

GEORGE N. MAS, OF WASHINGTON, DISTRICT OF COLUMBIA, ASSIGNOR OF ONE-HALF
TO CHARLES CHARUHAS, OF WASHINGTON, DISTRICT OF COLUMBIA.

DESIGN FOR A BOTTLE.

Application filed April 16, 1925. Serial No. 13,140. Term of patent 14 years.

To all whom it may concern:

Be it known that I, GEORGE N. MAS, a citizen of the United States, residing in the city of Washington, District of Columbia, have invented a new, original, and ornamental Design for Bottles, of which the following is a specification, reference being had to the accompanying drawing, forming part thereof.

The single figure of the drawing shows, in side elevation, a view of a bottle embodying my new design.

I claim:

The ornamental design for a bottle, as shown.

GEORGE N. MAS.
